The most interesting materials administered in doses greater than pharmacologically active ones and always orally to albino rats over several days showed no negative element; there was no modification of the weight increase graph, with respect to control animals, in the hematic formula and in the constant hemochromocitometric principles, no variation in hepatic activity and metabolism and the gastric tolerability is satisfactory.

The most interesting compounds of the invention from the pharmacological standpoint, when administered to

The compounds of the invention in general clearly affect sedation caused by barbiturates in mice, but only at elevated doses.

Several compounds of the invention have "in vitro" a clear inhibiting action on contraction of the isolated guineapig intestine, determined by barium chloride or by acetylcholine.

In Table I the most important properties of various compounds are tabulated (13, 14, 16, 21 the formulae of which are given in Table II).

TABLE I

Compound No.	acute toxicity DL ₅₀ , mg./kg.	Analgesic activity in mice						Sedative/tranquillising activity			
		Electr. stimulation tail		Phenyl-p-quinone		Hot plate		Inhib. excitation amphetamine		Rota-Rod	
		Dose, mg./kg.	Protect., percent	Dose, mg./kg.	Protect., percent	Dose, mg./kg.	Perman. iner. ¹	Dose, mg./kg.	Protect., percent	Dose, mg./kg.	Percent animals died ²
13-----	1,200	{ 5 10	{ 40 65	50	50	100	2.2	300	0	50	50
14-----	3,000	30	55	50	50	80	2.9	150	50	200	50
16-----	2,000	25	55	150	45	200	2.12	400	50	200	50
21-----	3,000	25	52	250	50	100	2.13	70	50	100	50

¹ Increase in time of permanence on the plate.

² Percent animals which died before the standard time.

anaesthetised cats (Nembutal) in doses higher than pharmacologically active ones showed no effect on the shape of the graph of pressure and respiration nor on the ECG trace.

They have a general analgesic action evaluated by the following tests:

- (a) pain electrostimulation of the tail in mice (Paalzov, L., Svensk farmaceutisk Tidskrift, 1962, 66, 860, except for some minor variations);
- (b) pain contractions in mice following intraperitoneal injection of phenyl-p-quinone (Siegmund, E., Proc. Soc. Exp. Biol. Med., 1957, 95, 729; Hendershot, L. C. For-saith, J., J. Pharmacol. Exptl. Therap., 1959, 129, 237);
- (c) hot plate with mice (Eddy, N. B., Leimbach, D. J., J. Pharmacol. Exptl. Therap., 1953, 107, 385).

The compounds of the invention have been studied also from the tranquilising activity/sedative standpoint, by the following tests:

- (a) "rota-rod" (rotating rod), (De Wied, D., Jenkins, R., Proc. Soc. Exptl. Biol. Med., 1958, 99, 44);
- (b) motive excitation caused by amphetamine, (Dunham, N. W., Muja, T. S., J. Amer. Pharm. Assoc., 1957, 46, 208).

Several compounds of the invention have an activity of this type.

Also, several other compounds have a convulsant action; this property has been studied by the methods:

- (a) of shock due to cardiazole (Riley, H., Spinks, A., J. Pharm. a. Pharmacol., 1958, 10, 657 and 721);
- (b) of shock due to strichine (Riley, H., Spinks, A., ibid);
- (c) electro-shock (Toman, J. E. P., Everett, G. M., Psychopharmacology-Cassel, London, 1958).

The compounds of the invention have been subjected to tests for anti-inflammatory activity, according to the test for experimental oedema of the rat paw, caused by:

- (a) carragenine (Winter, C. A., Proc. Soc. Exptl. Biol. Med., 1962, 111, 544);
- (b) kaolin (Coubon R., Arch. Int. Pharmacodyn., 1954, 99, 474);

and sometimes also by:

- (c) serotonin (Stone, C. A., J. Pharmacol. Exptl. Therap., 1961, 131, 73).

Several showed no antipyretic activity (or only very weak activity) by the test for experimental hyperpyrexia in rabbits caused by intravenous injection of polyvalent vaccine.

25 The following examples illustrate the invention without limitation:

EXAMPLE 1

N-[2'-(2'',2'',6'',6''-tetramethyl-piperid-1''-yl)-ethyl]-2,3-dimethylaniline

30 A mixture of 21.2 g. of 2,3-dimethylaniline, 24 g. of 2-(2',2',6',6'-tetramethyl-piperid - 1 - yl)-ethyl chloride hydrochloride, 27.6 g. of anhydrous potassium carbonate, 1 g. of copper powder and 150 ml. of anhydrous toluene were heated under reflux for 24 hours. After cooling, the solution was washed with 10% caustic soda solution and then with water. The dried organic phase was concentrated and distilled under vacuum to give 21 g. of an oil boiling at 165 to 160° C. at 0.1 mm. Hg. It was allowed to stand; a solid product of M.P. 39°-41° C. was obtained.

35 This base, when dissolved in isopropanol and treated with an isopropanol solution of hydrochloric acid, gives the hydrochloride which after crystallisation from methanol has an M.P. of 238°-240° C.

EXAMPLE 2

N-methyl-N-[2'-(2'',2'',6'',6''-tetramethyl-piperid-1''-yl)-ethyl]-3-chloroaniline

50 A mixture of 28.5 g. N-methyl-m-chloro-aniline, 24 g. 2-(2',2',6',6'-tetramethyl-piperid - 1' - yl)-chloride ethyl hydrochloride, 27.64 g. of anhydrous potassium carbonate, 1 g. of copper powder and 150 ml. of anhydrous toluene was heated under reflux for 24 hours. The mixture was cooled, filtered, washed with 10% NaOH and then with water. The dried organic phase was concentrated under vacuum and distilled to give 23.7 g. of an oil boiling at 180°-185° C. at 0.2 mm. Hg. This base, when dissolved in isopropanol and treated with hydrogen chloride gas, gives a hydrochloride having an M.P. of 160°-163° C. after recrystallisation from isopropanol.

EXAMPLE 3

65 N-carbethoxy-N-[2'-(2'',2'',6'',6''-tetramethyl-piperid-1''-yl)-ethyl]-2,3-dimethylaniline

70 14.4 g. of N-2'-(2'',2'',6'',6''-tetramethyl-piperid-1''-yl)-ethyl-2,3-dimethylaniline, 5.45 g. of ethyl chloroformate and 100 ml. of anhydrous benzene were heated under reflux for 8 hours. The mixture was cooled and treated with a dilute solution of NaOH and then with water. The dried organic phase was concentrated under vacuum and the residue was crystallized from hexane to give 12 g. of pure product; M.P. 75°-78° C.

5
EXAMPLE 4

N-propionyl-N-[2'-(2'',2'',6'',6''-tetramethyl-piperid-1''-yl)-ethyl]-3-chloro-aniline

14.75 g. of N-2'-(2'',2'',6'',6''-tetramethyl-piperid-1''-yl)-ethyl - 3 - chloro-aniline, 4.7 g. of propionyl chloride and 100 ml. of anhydrous benzene were heated under reflux for 6 hours. The cooled solution was treated with an aqueous solution of sodium hydroxide and then with water. The dried organic extracts were concentrated under vacuum and the residual oil was crystallised from isopropyl ether to give 13 g. of pure product; M.P. 118°-120° C.

EXAMPLE 5

N-(p-chloro-phenoxyacetyl)-N-[2'-(2'',2'',6'',6''-tetramethylpiperid-1''-yl)-ethyl]-2,3-dimethylaniline

14.4 g. of N-2'-(2'',2'',6'',6''-tetramethylpiperid-1''-yl)-ethyl-2,3-dimethyl-aniline and 10.25 g. of p-chlorophenoxyacetylchloride in 100 ml. of anhydrous benzene were heated under reflux for 8 hours. After cooling, the solid obtained was filtered and crystallised from isopropanol to give 20 g. of pure hydrochloride; M.P. 207°-209° C.

EXAMPLE 6

N - [2' - (1'',2'',3'',6''-tetrahydro - 2'',2'',6'',6''-tetramethyl-pyridyl - 1'') - ethyl] - 3 - (trifluoromethyl)-aniline

β -(1,2,3,6-tetrahydro - 2,2,6,6 - tetramethyl-pyridyl-1)-ethyl chloride hydrochloride (M.P. 222°-224° C.), prepared as the starting material for the synthesis of the product of the invention, was prepared by reacting 1-(β -hydroxyethyl) - 1,2,3,6 - tetrahydro - 2,2,6,6 - tetramethylpyridine (M.P. 72°-74° C.) with thionyl chloride under reflux in benzene solution and crystallizing from ethanol the product obtained.

A mixture of 32 g. of m-trifluoromethyl-aniline, 23.8 g. of β -(1,2,3,6-tetrahydro - 2,2,6,6 - tetramethyl-pyridyl)-ethyl chloride hydrochloride, 27.6 g. of anhydrous potassium carbonate, 2 g. of Cu powder and 200 ml. of anhydrous toluene was heated under reflux for 24 hours; after cooling, the solution was washed with 10% sodium hydroxide, then with water; the dried organic phase was concentrated and distilled under vacuum to give a yield of 19 g. of an oil boiling at 175°-180° C. under 0.8

6

mm. Hg; after several hours, a solid product was obtained having a melting point of 58°-60° C.

This base, when dissolved in acetone and treated with a hydrochloric acid solution in ethyl ether, gave a chloride which, after crystallization from isopropanol and drying under heat and vacuum, gave a melting point of 183°-186° C.

EXAMPLE 7

N-[2-(1',2',3',6'-tetrahydro-2',2',6',6'-tetramethyl-pyridyl-1')-ethyl]- α -phenethyl amine

24 g. of α -phenethylamine, 23.8 g. of β -(1,2,3,6-tetrahydro-2,2,6,6-tetramethyl-pyridyl-1)-ethyl chloride hydrochloride, 27.6 g. of anhydrous potassium carbonate, 3 g. of Cu powder and 200 ml. of anhydrous toluene were refluxed together for 44 hours; after cooling, the solution was washed with 10% sodium hydroxide solution and then with water; the dried organic phase was concentrated and distilled under vacuum to give 19.6 g. of an oil boiling at 149°-152° C. under 1 mm. Hg.

The phase dissolved in isopropanol and treated with an ethereal solution of hydrochloric acid gave the hydrochloride, which after crystallization from 95% ethanol gave an M.P.=226°-227° C. (with decomposition).

EXAMPLE 8

N-[2-(1',2',3',6'-tetrahydro-2',2',6',6'-tetramethyl-pyridyl-1')-ethyl]furfuryl-amine

19.4 g. of furfurylamine, 23.8 g. of β -(1,2,3,6-tetrahydro-2,2,6,6-tetramethyl-pyridyl-1)-ethyl chloride hydrochloride, 27.6 g. of anhydrous potassium carbonate, 2 g. of Cu powder and 200 ml. of anhydrous toluene were refluxed together for 30 hours; after cooling, the solution was washed with 10% sodium hydroxide and then with water; the dried organic phase was concentrated and distilled under vacuum to give 21 g. of an oil boiling at 135°-139° C. under 0.5 mm. Hg.

The base, dissolved in isopropanol and treated with hydrochloric acid in isopropanol, gave a dichloride which after crystallization from ethanol, gave a melting point of 212°-213° C. (with decomposition).

Various other compounds according to the invention have been prepared; the principal results are given in Table 1.

The principal compounds so made are tabulated in Table II.

TABLE II

*Crystallization with 1/2 molecules of isopropanol.

We claim:

1. A compound selected from the group consisting of: 40 (a) a compound of the general formula:

wherein R₁ is selected from the group consisting of phenyl, chlorophenyl, tolyl, chlorotolyl, dichlorophenyl and xylyl; and

(b) a pharmaceutically acceptable acid addition salt thereof.

2. The compound of claim 1 which is N-[2'-(1'',2'',3'',6''-tetrahydro-2'',2'',6'',6''-tetramethyl-pyrid-1''-yl)-55 pp. 495-496, 1961, QD 251F5a.

3. The compound of claim 1 which is N-[2'-(1'',2'',3'',6''-tetrahydro-2'',2'',6'',6''-tetramethyl-pyrid-1''-yl)-ethyl]-2,3-dimethyl-aniline dihydrochloride.

4. The compound of claim 1 which is N-[2'-(1'',2'',3'',6''-tetrahydro-2'',2'',6'',6''-tetramethyl-pyrid-1''-yl)-ethyl]-2,3-dichloro-aniline dihydrochloride.
